(57) **CLAIM**

I claim the ornamental design for a device for insertion of objects, in particular implants, into the body of humans and/or animals, as shown and described.

DESCRIPTION

FIG. 1 is a top view of a device for insertion of objects, in particular implants, into the body of humans and/or animals of the present invention;

FIG. 2 is a bottom view thereof;

FIG. 3 is a front end view thereof;

FIG. 4 is a back end view thereof;

FIG. 5 is a cross-sectional view of section 5-5 thereof;

FIG. 6 is a cross-sectional view of section 6-6 thereof;

FIG. 7 is a left side view thereof;

FIG. 8 is a right side view thereof;

FIG. 9 is a perspective view thereof;

FIG. 10 is another perspective view thereof;

FIG. 11 is a perspective view thereof in an alternate state; and,

FIG. 12 is a perspective view thereof in another alternate state.

1 Claim, 8 Drawing Sheets
